(57) **CLAIM**

The ornamental design for a handle for a serving utensil, as shown and described.

DESCRIPTION

FIG. 1 is an isometric view of a serving utensil having a handle, embodying a new design;

FIG. 2 is a front elevation view thereof;

FIG. 3 is a rear elevation view thereof;

FIG. 4 is a side elevation view, the opposite side being a mirror image thereof;

FIG. 5 is a top plan view thereof; and,

FIG. 6 is a bottom plan view thereof.

The broken lines shown in the drawings are for illustrative purposes only and form no part of the claimed design.
